(54) **THRASHING MACHINE**

(76) Inventor: **Henry Heberling**

Henry Heberling, Shott Creek Township, Ohio
Peterson's Patent

The Schedule referred to in these Letters Patent and making part of the same containing a description in the words of the said Henry Heberling himself of his improvement in the Machine for thrashing grain.

It will be when these presents shall come. Be it known that I Henry Heberling of Shott Creek Township in the County of Harrison & State of Ohio have invented a new and useful improvement in the machine for thrashing grain, and that the following is a full and exact description of the construction and operation of this said machine as invented or improved by me. The machine consists of the following principal parts viz. 1st the frame. 2nd the thrashing cylinder. 3rd the concave. 4th the feeding board.

1st The frame may be made of any convenient size and strength adapted to the machinery to be constructed thereon, by morticing and tenoning together four posts to the side and end pieces, & rabbling the side boards into the posts to receive the concave. 2nd The thrashing cylinder is constructed by first making an axis about one and a half inches in diameter with two wood or metal heads, one for each end. If made of wood they must be plated with iron, if of metal there may be eight holes drilled through each end through which the staves may be bolted on with iron bolts for the convenience of turning off the cylinder. The diameter of the rings may be about thirteen inches. The staves are next to be placed in the length of the intended cylinder, and of such a thickness as will allow the cylinder when finished to be about nineteen inches in diameter. The teeth are made of wrought iron half an inch square and wedged on the face and left square on the back tapering from full three eighths of an inch at the bottom to about one quarter of an inch at the outer end, and rather broad extending back that they may not bend. They should project from the surface about two and a quarter inches when mounted and be about one and one eighth of an inch apart from center to center, and clenched, bending back or declining from the grain rather than otherwise, The number of teeth in a full horse power may be about one hundred and ninety

and must be so inserted as to save the timber as much as possible and interval reciprocally show in the concave herein after described. 3rd The concave must be made of the same curvature as the extremity of the teeth in the cylinder and is to contain three solid rows and two half rows of teeth of the same dimensions and same distance from center to center as those in the cylinder. These are to be inserted and secured in five round wrought iron rollers about one inch in diameter with the holes drilled for this purpose. The two half rows or half filled rollers must go in the front of the concave. These rollers must be sunk in the concave until they drop parallel with the surface of the concave and form a part of it. The surface of the concave immediately below or behind the rollers must be cut away until the teeth may be permitted to lie or spring down flat to the bed in the event of any hard substance or large bunch of grain falling accidentally into the machine so that after such hard substance or sheaf passes through the rollers being sustained by springs of a proper strength instantly raise the teeth to their proper position. These springs act on one end of each roller. A wire passes through the side board of the machine, it extending also far enough into the side board on the opposite side to make it completely strong; each roller may also be supported in the middle if thought proper. Steel wire or any kind of springs may be used that may meet the choice and convenience of the builder. It may however be found convenient to put them on the side opposite to the wheel and to place them above connecting them to wheel bows slipped on the end of each roller, the ends being made square for that purpose. The teeth in the concave should decline from the grain that it may not be detained too long in getting through, and this may be regulated by inserting small pins above the teeth. The concave should be placed either in front of the cylinder and may extend there or you may place post the center bar neck forming about one fourth of the circumference of the cylinder. As the concave and cylinder both should be covered with sheet iron care must be taken in putting it on especially on the concave that after each roller should be so covered as to run down between the teeth so that it should not interfere with the springing down of the teeth. 4th The feeding board is an inclined plane placed in front of the cylinder and even with the top of the concave. Operation. - The grain to be threshed is introduced into the machine along the feeding board. it is conveyed by the cylinder to the concave bed where it is rubbed out between the teeth

when grain and Straw both pass out together the Straw remaining completely on top. By means of these Rollers many accidents detrimental to the machine and dangerous to the Thrasher will be avoided and none of that waste of power caused by a flexible cylinder (its being continually more or less out of Balance) can occur. What I claim as my invention and not previously known in the above described machine is particularly the spring Rollers, and their application to a concave for threshing grain - I testify that the above is a full and exact description of the construction and mode of operation of my improvement as invented or improved by me. I have hereunto set my hand this second day of April in the year Eighteen hundred and thirty five
